(54) **BOOTS & SHOES, WATER PROOF**

(76) Inventor: **Patrick G. Nagle**

Patrick G. Taylor, residing in the United States, in the County of Worcester, State of Massachusetts, in the Commonwealth of Massachusetts,
Inventor of the material for
the manufacture of leather
therein incorporated, to wit,
Date of Patent March 12, 1820.
Published in the Boston Advertiser.

The substance referred to in the above-mentioned
patent, part of the same or, by way of description
in the words of the said Patrick G. Taylor, is
as follows: improvement in the manufacture
of leather and shoes, and in the preparation
composition of the leather or its for the manufacture
to render them impervious to water.

The following are the materials used, and
the mode of using them, to make leather and
shoes impervious to water: take
two quarts of Linseed Oil 2 lbs of mutton
fat, 2 lbs of lard, 1 lb of bacon, and
1 pint of salt; put them all together into a
large earthen vessel and let the mixture
boil for about two minutes, dissolve them
over a slow fire and let it remain in the
vessel until it becomes quite warm.

In that state apply it so as may suffice
to make the upper leather, when so done
allow it to dry, stretched on the principle boards
in order that it may penetrate every part of the
leather, when it is to be used.

first warm, and rub it well with the animal
gut, and then with the silk, then
and apply it between the upper leather and
the lining of the foot of the boot or shoe upon
the inside by the silk they prepared before
and between the upper leather and lining
of the shoe. For making the sole of leather
I use the same as I do to make it as above
described. And the paste is warmer when it
is used and by a piece of it, the whole size
of the foot between the two leather shoes being
rubbed with the prepared paste to cover the
shoeing on the inside.

Patrick J. O'Fyle
